ARCHIE DI GRAZIA AND RAY BIAGINI, OF CHARLEROI, PENNSYLVANIA.

SELF-PROPELLED AERIAL BOMB.

1,327,810.

Specification of Letters Patent. Patented Jan. 13, 1920.

Application filed June 3, 1918. Serial No. 237,874.

To all whom it may concern:

Be it known that we, ARCHIE DI GRAZIA, a subject of the King of Italy, and RAY BIAGINI, a citizen of the United States, residing at Charleroi, in the county of Washington and State of Pennsylvania, have invented certain new and useful Improvements in Self-Propelling Aerial Bombs, of which the following is a specification.

10 Our invention relates to improvements in aerial bombs and has for its object to provide a device of this class embodying a self-propelling dirigible vessel containing a prime mover of suitable type adapted to be operated for a definite period and to be then discontinued, whereupon the propulsion of the device will terminate and it will fall by gravity until coming into interference with any obstruction, resulting in an explosion and destruction of the mechanism with accompanying distribution of projectiles and fuel in combustion, as more fully hereinafter described.

25 Referring to the drawings illustrating certain preferred embodiments of the invention—

Figure 1 is a view in elevation showing the device in position for making a flight;

Fig. 2 is an end elevation from the rear;

30 Fig. 3 is an enlarged longitudinal horizontal section, partly broken away, indicated by line III, III of Fig. 1;

Fig. 4 is a view showing a modified construction of the primer pins; and

35 Fig. 5 is a cross section on the line V, V of Fig. 3.

Fig. 6 is a diagram showing a conventional ignition system for the engine.

The body of the device is generally cigar shaped, or of other suitable form, adapting it for travel through the air with a minimum of resistance, and is inclosed within a surrounding shell 2 of sheet metal or other suitable material, the rear portion 2' containing the main explosive charge being preferably of a thin shell of aluminum. Within said aluminum shell and arranged centrally of the body portion is the main explosive-containing shell 3, preferably of steel, containing a charge of high explosive 4 of any suitable material as powder or T. N. T. Surrounding said explosive and contained within an outer surrounding shell 5 is a charge of bullets, shrapnel or the like 6, adapted to be scattered in various directions upon explosion of the main charge 4.

Between the shrapnel charge and the outer shell or casing 2' is a surrounding annular cavity which is filled with gasoline or other highly combustible fluid mixed with a suitable proportion of waste or other similar material as indicated at 7, adapted to hold portions of the combustible fluid when scattered in various directions, whereby to maintain continuous combustion thereof. 60 65

The main vessel is provided with suitable wings or planes 8—8 extending laterally at each side and of proper size and proportions to maintain the vessel in continuous flight under impelling action of a propeller 9. 70 Said propeller is mounted upon the forward end of the driving shaft 10 which is actuated by a fluid combustion engine 11 of any suitable type, but preferably a gas engine utilizing gasoline as fuel. Gasoline for 75 such purpose is contained in tank 12 at or about the middle body portion of the vessel, shell or casing 2 and terminal end walls 13—14 respectively. Between front wall 13 and the supplemental comparatively 80 thin wall 15 is a supplemental charge of explosive 16 in communication with the main explosive charge 4 by a fuse 17 within a communicating tube or conduit 18. Forwardly of partition 15 and within a suitable casing 19 is an initial explosive charge 20, the purpose of which is to destroy the ignition connections from a battery or magneto to the spark plugs of engine 11 for the purpose of rendering such engine ineffectual 85 upon explosion of the charge 20, so as to terminate operation of propeller 9. The electrical circuit connections for the ignition are merely indicated by wires or other suitable connections 21 leading to a commutator 95 22 of usual construction and adapted to be rendered useless upon explosion of charge 20. Any suitable wiring for the circuit may be adopted, as indicated in Fig. 6.

It is designed that charge 20 may be ignited at any predetermined time after the commencement of the flight of the machine, for which purpose we use a time fuse 23 inserted into communicating contact with charge 20 so that, depending upon the length 105 of the fuse and the time of its combustion, the explosion will take place at a certain number of seconds or minutes after the machine is started. The engine is surrounded by a casing 2 as indicated, and is provided 110 with one or more hinged hoods or doors 24 for access to the interior, as will be readily

understood. Gasolene is furnished to the engine through a suitable carburetor 25 from tank 12, as indicated, and the several parts of the engine are similar to the usual gasoline motor commonly employed in aeroplane and automobile work.

The machine is provided with upper and lower stabilizing fins 26-27 properly braced as indicated, and planes 8 are also 10 preferably arranged in the manner indicated in Fig. 1, inclining upwardly toward the front, whereby to facilitate rising or soaring action.

The rear end of the machine is closed by a 15 terminal cap 28, preferably of steel, suitably connected to the main body portion, within which is provided a steel plug 29 having a central port 30 in direct communication with main charge 4. Plug 29 is provided 20 with a central primer 31, and a plurality of firing pins 32 are mounted in divergent arrangement as indicated, each pin being adapted to be brought directly into firing contact engagement with the primer 31 upon 25 coming into contact with any obstructing object so as to fire the explosive charge 4. Pins 32 are slidably mounted in the outer portion of cap 28 and are preferably maintained in retracted or extended position by 30 spiral spring 33, easily compressible upon exertion of a forcible thrust inwardly of either pin. Each pin is also preferably provided with a series of slopingly arranged spurs or barbs 34, projecting angularly as 35 indicated, so as to insure engagement against any obstructing object, as for instance, wires, foliage, or the like.

For the purpose of starting the apparatus in flight at any desired angle, we preferably 40 employ an adjustable skidway or platform 35 having side bars 36, upon which supporting wheels 37 of the machine are adapted to run. Said wheels are located in suitable positions at the terminals of conveniently arranged frames 38, wheels 37 being located 45 sufficiently apart to stabilize the machine in starting. Skidway 35 may be adjustable with relation to a horizontal base 39 by any suitable means, as gearing 40 and a screw 41, 50 the skidway being pivotally mounted at one end as indicated at 42.

The construction and operation of the invention will be readily understood and appreciated from the foregoing description. 55 Engine 11 being actuated by propeller 9 will carry the machine along upon wheels 37 until it is in flight, and the machine will travel in the desired direction and for the desired distance during the predetermined 60 period of time, whereupon, fuse 23 will ignite charge 20, will destroy the engine ignition, and thus result in stoppage of the propeller. Thereupon the machine will assume an approximately vertical position by gravitation, 65 tipping backwardly and falling vertically,

because of the greater weight contained in its rear end, and will fall until one or more of the igniting pins 32 strikes an interfering object resulting in ignition of the primer of the main charge, with the resulting explosion of supplemental charge 16, resulting in complete destruction of the device itself, violent distribution of the shrapnel, and the gasoline-invested waste or the like, with the accompanying destruction or conflagration 75 of any object which is the intended destination of the bomb.

What we claim is:

1. An aerial bomb consisting of an inclosing shell having a main explosive charge, a 80 primer, and a barbed firing pin therefor at one end, and a propeller, an engine geared therewith, and an engine impairing explosive charge at the other end, and a time fuse for said explosive charge.

2. An aerial bomb consisting of an inclosing shell having a main explosive charge and a surrounding charge of inflammable fluid, a primer for the main charge, a firing pin therefor, a propeller, an engine geared therewith, an engine-impairing explosive charge, and a time fuse therefor, a supplemental explosive charge adjacent the engine, a fuel tank between the main and supplemental charges, and a fuse connecting 90 said charges extending through the fuel tank.

3. An aerial bomb consisting of an inclosing shell having at one end a main explosive charge, a primer therefor having a spring-retracted barbed firing pin operable upon impact, a contained body of inflammable fluid and portions of soaking material mixed therein, and at the other end a propeller, an engine geared therewith, a fuse-ignited 100 charge of explosive adapted to render the engine inoperative, and a gasoline supply tank for the engine midway of the shell.

4. An aerial bomb consisting of an inclosing shell having at one end a main explosive 110 charge, a primer therefor having a spring-retracted barbed firing pin operable upon impact, a contained body of inflammable fluid and portions of soaked material mixed therein, and at the other end a propeller, an engine geared therewith, a fuse-ignited 115 charge of explosive adapted to render the engine inoperative, supporting and guiding planes for the bomb, and a gasoline supply tank for the engine midway of the shell.

5. An aerial bomb of the class described consisting of a shell-like body portion provided with a main explosive charge at one end and a spring-retracted barbed firing pin and igniting primer therefor, a propeller 125 and an engine therefor at the other end provided with means rendering the engine inoperative at a predetermined time, an engine-destroying explosive charge, a gasoline supply tank for the engine between it and 130

the main explosive charge, and supporting and stabilizing planes for the bomb.

6. An elongated aerial bomb having a main explosive charge at one end adapted to be fired by impact, a propeller and a motor and ignition mechanism therefor at the other end, planes adapted to maintain the bomb in continued flight, and an explosive charge in disruptive relation to the ignition mechanism having a time fuse for stopping the en-

gine and propeller whereby the bomb will become overbalanced by the main explosive charge and will tilt backwardly and fall by gravity and explode upon striking an interfering object.

15

In testimony whereof we hereunto affix our signatures.
